FRIEDRICH MARTIN, OF ESSEN, GERMANY, ASSIGNOR TO FRIED. KRUPP AKTIEN-
GESELLSCHAFT, OF ESSEN-ON-THE-RUHR, GERMANY.

CONTROLLING APPARATUS FOR PISTON PUMPS.

1,418,951.

Specification of Letters Patent. Patented June 6, 1922.

Application filed October 4, 1920. Serial No. 414,690.

To all whom it may concern:

Be it known that I, FRIEDRICH MARTIN, residing at Essen, Germany, a citizen of the German Republic, have invented a certain new and useful Improvement in Controlling Apparatus for Piston Pumps, of which the following is a specification.

- The present invention relates to regulating devices for piston pumps with shaft 10 drive and variable stroke-length, in which a starting or regulating piston, intended to adjust the stroke-length of the pump piston during the operation of the pump, is influenced by the fluid pressure, generated by 15 the pump, and also by a power source counteracting said pressure; so that the fluid pressure tends to set or adjust the starting piston in the direction of a diminished stroke-length. When the greatest piston 20 stroke-length in pumps of known art is selected for mean water consumption, it will be necessary to use an accumulator which delivers the additional quantity of water during greater water consumption. 25 The object of the present invention is to provide a regulating device, so that the contents of the accumulator may be utilized to the greatest possible extent.

- One embodiment of the present invention 30 is illustrated in the accompanying drawing, showing in Fig. 1 a side elevation, partly in section, of a regulating device, together with appurtenant parts of the pumping plant and Fig. 2 on a larger scale a similar view of 35 means for varying the stroke length of the pump. And this embodiment also shows how it is possible to provide a very gentle transit of the starting piston from its position, corresponding to the greatest stroke-length, into the position corresponding to a 40 diminished water consumption; in case the water consumption is diminished from a quantity in excess of the greatest production of the pump to a quantity which is smaller 45 than this production.

- A is the casing of the piston-pump, to which suction pipe a' and pressure pipe a^2 are connected. The pump is provided in the usual way (Fig. 2) with several stationary 50 cylinders A^5 , arranged parallel to their drive

shaft B. In each cylinder A^6 is guided a piston L, which is connected by a rod Q with a cam disc R, which in turn is connected with the casing A by a cross comprising two pairs of pins r' and S, arranged at right angles to each other. The axes of the two pairs of pins r' and S intersect in a point o , forming the center of the cross, and lying in the axis of the shaft B. Cam disc R bears through a ball bearing T on a bearing member B' , which is so adjustably mounted on a disc B^2 , rigidly connected with the shaft B, that it can turn relatively thereto about an axis which stands at right angles to the axis of the shaft B in the center point o of 55 the cross r' , S. To adjust the bearing member B' , a sleeve C is provided, which is slideable but not rotatable on the shaft B, driven, for example, by an electric motor of constant speed. The sleeve C is provided on both 60 sides of the shaft B with rack bar c^2 , which engages a gear sector U. Each of the sectors U is rotatably journaled on a bridge b^3 rigidly connected with the disc B^2 , and meshes with a gear segment b^4 , mounted on 65 the bearing member B' , so that the latter can be turned relatively to the disc B^2 , rigidly connected with the shaft B, by a displacement of the sleeve C about its axis passing through the point o . By this displacement 70 of the sleeve C a variation of the length of the stroke of the piston L can be brought about in a known way, and a shortening of the length of stroke takes place when the 75 muff C is displaced in the direction of the arrow x . With a stud d' one arm of the bell-crank D engages a groove c' in the muff C, the arm being pivotally attached to the housing A of the pump. The other arm of the bell-crank D is, by means of an intermediary 80 link E, connected with a single-armed lever F, which is pivotally secured on the housing A. This lever is positively connected with a piston rod H' , of a starting piston H running in a cylinder A^8 , through the intermediary of a sliding piece G, hinged to the lever and running in a slot in the piston rod H' .

Every position of the starting piston H corresponds then with an exact position of 100

the muff C, and, as a consequence, with an exact stroke-length of the pump piston. The starting or regulating piston is represented on the drawing in a position corresponding to the greatest stroke-length, in which the production of the pump is equal to the mean water consumption in the pressure conduit. The direction in which the piston H moves during a diminution of the stroke-length is indicated by an arrow y. The cylinder A³ stands in connection with the pressure conduit a² through a pipe a⁴, which is attached to the right end of the cylinder, where the piston rod H' extends. The left end of the cylinder A³ is, by means of a pipe J, connected with a pressure tank (not shown) acting as power source.

The accumulator is provided with a disk piston K, having a piston rod on one side and running in an upright standing cylinder M. At its upper end where the piston rod K' goes through, the cylinder M is connected with the pressure conduit a², through a passage m', and at its lower end, through a passage m², it is connected with the pipe J which leads to the pressure tank (not shown).

The active pressure area of the piston K, at the end nearest the pressure tank, is denoted by F_k, and the smaller active area at the end nearest the pressure conduit of the pump is denoted by f_k. The corresponding values for the regulating piston H are F_h and f_h. The proportions have now been selected in accordance with the present invention, so that

$$\frac{f_k}{F_k} \text{ is greater than } \frac{f_h}{F_h}$$

At its upper end the piston rod K' is provided with a collar k² with which it abuts against a helical spring P through the intermediary of a pressure plate N surrounded by a cap m³ when the piston has reached within a certain small distance from the bottom of the cylinder M, as shown by dot-and-dash lines on the drawing. When the piston gets still closer to the bottom of the cylinder, the spring becomes compressed and tends to lift the piston.

In describing the manner of operation of the pumping plant, it will be supposed that first the water consumption is greater than the production of the pump, so that the excess water consumption must be compensated for by the accumulator. During the condition of inertia, the accumulator piston K moves with uniform speed upwards after the spring has been liberated by the collar k² off the piston rod K'. The correct fluid pressure existing over the piston is now denoted by p_m, while the power source pressure under the piston is denoted by p_o. The load of the accumulator piston, through the

power source pressure, is consequently p_o, F_k. The following equation may now be written if the piston friction and weight are neglected:

$$p_m \times f_k = p_o F_k$$

or

$$p_o = p_m \frac{f_k}{F_k}$$

On the regulating piston H the fluid pressure now acts, in the direction of the arrow y, with a force of a magnitude

$$p_m \times f_h$$

and in the opposite direction the power source pressure acts with a force of the magnitude

$$p_o F_h = p_m \frac{f_k}{F_k} \times F_h$$

In opposite direction to arrow y a resultant force consequently acts of a magnitude

$$p_m \frac{f_k}{F_k} \times F_h - p_m f_h = p_m F_h \left(\frac{f_k}{F_k} - \frac{f_h}{F_h} \right)$$

As now the proportion $\frac{f_k}{F_k}$ is greater than $\frac{f_h}{F_h}$, consequently the resultant force acting in opposite direction to arrow y is always positive and becomes so great, by suitable selection of values $\frac{f_k}{F_k}$ and $\frac{f_h}{F_h}$, that the regulating piston H, in the case under consideration, always adjusts itself accurately in the position that corresponds to the greatest stroke-length. The regulating piston can

not therefore, clearly adjust itself in any position that represents a shorter stroke-length, which by longer continuation of the water consumption in excess of the greatest production of the pump, would cause a too early emptying of the accumulator.

Supposing now, that the water consumption becomes less than the greatest water production of the pump; the excess quantity of water produced by the pump then flows through the passage m' in the accumulator and the piston K moves downwardly. The fluid pressure existing above the piston K, then at first remains practically constant and the regulating piston H is therefore further held in its position representing the greatest stroke-length. This condition remains until the collar k² of the accumulator piston strikes the pressure plate N, and the piston consequently reaches its almost lowest position. A further movement of the accumulator piston is now only possible with a compression of the spring P. The fluid pressure above the accumulator piston and in the pressure conduit must consequently

increase during continued compression of the spring. Finally, the force, acting in the direction of the arrow y and generated by the fluid pressure on the regulating piston 5 H , attains an excess over the forces acting in the opposite direction, and the regulating piston H starts now in the direction of a shortened stroke-length of the pump.

By suitable selection of proportions and 10 particularly by correct choice of strength for spring P , it can be easily attained that at the beginning of the movement of the regulating piston H , a sufficiently greater fraction 15 of the excessive quantity of water enters the accumulator, so that during the acceleration of the regulating piston H and the other regulating parts which are displaced by the latter, there will be avoided, with certainty, undesirable shocks.

20 As soon as the regulating piston has arrived in the position wherein the production of the pump is the same as the water consumption in the pressure conduit, the piston comes to a standstill. Then a fluid pressure 25 will occur in the pressure conduit that lies so much above the normal operating pressure p_m , that it equalizes the force acting upon the regulating piston generated by the power source pressure p_o . Simultaneously 30 the accumulator piston K comes to rest in its lowest position, when the spring P is compressed so much that the spring pressure and the force exerted upon the piston K by the power source pressure p_o equalize the 35 force exerted by the increased fluid pressure.

If thereupon a water consumption should take place, that is in excess of the production of the pump corresponding to the greatest 40 stroke-length, then the fluid pressure in the pressure conduit sinks so that the equilibrium is broken between the force acting against the regulating piston H and the force acting against the accumulator piston 45 K . Both pistons then start to move; the regulating piston H in the opposite direction to arrow y , or, in other words, in a direction of an increase of the stroke-length of the pump; and the accumulator piston K 50 in an upward direction. As soon as the accumulator piston has risen so high that the collar k^2 has released the spring P , the correct operating pressure p_m will again be obtained in the pressure conduit, through 55 which the force exerted by the power source pressure p_o upon the regulating piston H will be in excess of the forces acting in the

opposite direction, as has been described hereabove.

Claims.

1. A regulation device for piston pumps with shaft drive and variable stroke-length, comprising an accumulator cylinder connected to the pressure conduit of the pump, a piston in said cylinder and means for controlling the fluid pressure therein whereby the fluid pressure may be increased when the accumulator piston has been displaced by the fluid pressure to the end of its stroke, a regulating cylinder likewise connected to the pressure conduit of the pump, a piston in said regulating cylinder controlling the stroke-length of the pump piston during the operation of the pump, said controlling piston being adapted to be displaced by the fluid pressure in the direction of a diminished stroke-length, and means whereby the controlling piston is automatically operated in opposite direction, said controlling piston being so proportioned that it is held in a position corresponding to the greatest stroke-length, before the fluid pressure in said accumulator cylinder has been increased by said fluid pressure controlling means. 60 65 70 75 80

2. A regulating device in accordance with claim 1, wherein the means for controlling the fluid pressure in the accumulator cylinder are adapted to be actuated by the movement of the accumulator piston when near its extreme position which corresponds to 90 the greatest accumulator contents. 85 90

3. A regulating device in accordance with claim 1, wherein the accumulator and the controlling piston are constructed as disk pistons, said pistons having different areas 95 on both sides thereof, said accumulator cylinder and regulating cylinder being connected on the side of the greater area with a pressure tank, the proportion between the smaller and the larger pressure areas of the 100 accumulator piston being greater than that for the controlling piston.

4. A regulating device in accordance with claim 2, wherein the accumulator cylinder is provided with a spring, said spring being 105 positioned so as to be engaged by the accumulator piston, substantially as and for the purpose set forth.

The foregoing specification signed at Essen, Germany, this 17th day of June, 1920. 110
